ELECTRIC FLATIRON

Maurice H. Graham, St. Louis Park, Minn.

Application June 15, 1934, Serial No. 730,745

7 Claims. (Cl. 219—25)

My present invention relates to electrically heated flatirons and, generally stated, the invention consists of the novel devices, combinations of devices and arrangement of parts hereinafter described and defined in the claims. The accurate regulation of heat in an electrically heated flatiron involves problems that are peculiar to flatiron structures. The sole plate of the flatiron, in use, will be subjected to various different heat-absorbing conditions, sometimes to delicate materials such as laces, chiffons and the like, which absorb heat very slowly, and sometimes to damp blankets and the like, which absorb heat very rapidly. In practice and in accordance with underwriters' rules and regulations, one thousand watts is about the limit which can be supplied to an electrical flatiron or to any other current-utilizing device over the ordinary wires of a house installation.

Experience has shown that cast iron is the best metal for use in the sole plate of an electrically heated flatiron. By experiment I have found that for the greatest accuracy of heat control, the switch actuator should be incorporated in the sole plate and should be of a metal that has a lower co-efficient of expansion and a slower rate of heat exchange than the cast iron sole plate. I have further found that the efficiency of the iron will be increased by incorporating the electric heating element also in the sole plate of the flatiron. The problem has been to find a metal for use as a switch actuator which will not only have a lower co-efficient of expansion than cast iron, but will maintain a constant or even rate of expansion and contraction at the high temperatures at which flatirons should be maintained in use.

Cast iron has been found to be the best for the sole plate of a flatiron. I have obtained substantially perfect results by making the switch actuator in the form of a metal alloy bar or rod closely embedded in the groove or slot in the sole plate and made of a nickel-steel alloy, to wit: an alloy consisting of 42% nickel and 58% steel. The co-efficient of expansion of cast iron is .059, and that of the nickel-steel alloy .026. When thus made, the sole plate will have more than twice the expansion of the nickel-steel actuator bar. Moreover, the cast iron of the sole plate will absorb and radiate heat faster than the nickel-steel actuator bar, which action, together with the fact that the actuator is embedded in the sole plate, give an ideal action that will hereinafter more fully appear.

The proportions of nickel and steel in the above alloy are of great importance. A nickel-steel alloy consisting of 36% nickel and 64% steel is a metal known as "invar metal." This invar metal, as is well known, expands and contracts very slightly in temperatures below 350 degrees F., but at temperatures above 350 degrees F., it expands very rapidly and unevenly so that it cannot be relied upon for accurate control of a flatiron, the temperature of which should be around 500 degrees F. At 500 degrees F., invar and cast iron have substantially the same co-efficients of expansion. However, the 42% nickel—58% steel alloy has an even rate of expansion and contraction at all temperatures below 650 degrees F.

By experiment I have found that the nickel employed in the nickel-steel alloy for the switch actuator must not be less than 40% or more than 50%. The above 42%—58% nickel-steel alloy in the form of a bar is not fragile, has good strength and when embedded in the sole plate as stated, has been found to give a switch control that is almost perfect in its accuracy. As a further important characteristic this nickel-steel alloy, in respect to cast iron, has a slower rate of heat exchange, that is, will not cool as rapidly or absorb heat as rapidly as cast iron.

The invention above outlined is illustrated in the accompanying drawing, wherein like characters indicate like parts throughout the several views.

Referring to the drawing:

Fig. 1 is a vertical section taken longitudinally through the major axis of an electric flatiron embodying my invention and illustrating a very desirable form thereof, some parts being shown in full;

Fig. 2 is a vertical section of the iron shown in Fig. 1, with the handle, casing and certain other parts removed, and some parts broken away; and

Fig. 3 is a fragmentary section taken on the line 3—3 of Fig. 2.

Referring to the drawing, the numeral 9 indicates the sole plate of a flatiron which is of cast iron; and the numerals 10, 11 and 12 indicate, respectively, the metal anchoring plate, the sheet metal shell or cover and the handle of the flatiron. The said parts 9 and 10 are shown as rigidly but detachably connected by screws 13 and the said elements 10, 11 and 12 are shown as rigidly but detachably connected by screws 14. For the highest efficiency, the electrical heating element, which is formed by

manifold wire coils 15, is embedded in the sole plate 9. Preferably, this embedding of the coils 15 is accomplished in a manner disclosed and claimed in my pending application, Serial No. 705,716, filed January 8, 1934, entitled "Electrical heating element for flatirons and the like and process of producing and installing the same."

Briefly described, this scheme of application 10 of the coils in the sole plate consists in providing the sole plate, on its upper surface, with depressions to receive tiles 16 which, in turn, are formed in their under sides with depressions that receive cement 17 in which the coils 15 are 15 directly embedded and brought close to the bottom of the sole plate, all as more fully disclosed in my said pending application. As shown, there are two manifold coils 15, the terminals of which are indicated at 15a and 15b.

20 On the heel of the shell or cover 11 are the usual circuit lead terminals 18, to which the socket of an electric supply cable is adapted to be connected in the well-known manner.

The supply circuit to the heating coils 15 25 includes an electric switch which may take various forms but which, as illustrated in these views, Figs. 1, 2 and 3, includes contact points 19 and 20 carried by the up-turned prongs of a U-shaped spring switch 21, the lower portion of which is anchored to the sole plate 9 by a short cross bar 22 which, in turn, is rigidly but detachably secured to the sole plate by screws 23 or the like. The contact point 19 is 30 electrically connected by a flexible metal ribbon 24 to one of the terminals 15a of the heating coil, and the other of said terminals 15a will, by a wire, not shown, be connected to the other lead terminal 18, to wit: the lead terminal to which the ribbon 25 is not connected. The said lead terminals 18, of course, are insulated the one from the other. The coil terminals 15b are 35 electrically connected by a suitable conductor indicated in Fig. 2 at 26. The rear prong of the spring support 21 is adapted to be variably set; and this, as shown, is accomplished by a pressure screw 27 that works through a post 28 anchored to the heel or rear portion of the sole plate.

The switch actuator used in the iron illustrated in the drawing is shown as in the form of a flat bar 29, made of the nickel-steel alloy above described. This actuator bar is incorporated in the sole plate and is quite closely fitted into a longitudinal groove 30 formed at the longitudinal axis of the sole plate and extended at its rear portion into a small well or depression 31 in which the lower portion of the switch 21 is shown as mounted.

At its rear end, switch actuator bar 29 is shown 60 as provided with an upwardly and rearwardly projecting finger 32 that works through a perforation in the front arm of the switch 21 and has a projecting lug that exerts a forward pull on the front arm of the switch 21 in the switch-actuating operation presently to be noted. At 65 its front end, bar 29 is shown as provided with a small depending anchoring lug 33 that engages a depression in the sole plate and is held in such engagement by a lock screw 34 or the like applied to the sole plate.

The co-efficient of expansion of cast iron, as above indicated, is .059, while that of forty per cent nickel-steel is .026. Assuming these facts, it is evident that when the iron is cold, the spring tension in the switch 21 will hold the

contact points 19 and 20 in engagement, thereby closing the circuit through the electrical heating elements of the flatiron, providing, of course, that there is a supply of current to the terminals 18. When heat is applied to the sole plate 5 from the electrical heating coils, the sole plate will, with the materials above indicated, expand more than twice as fast as the actuator bar 29, and hence will exert a forward pull on the bar 29; and at some certain temperature, the 10 bar 29, acting on the front arm of the switch 21, will separate the contacts 19 and 20, thereby automatically cutting off the supply of current to the heating elements.

The temperature at which the contacts 19 15 and 20 will be separated and the current cut off in the iron, may be varied by forward and rearward adjustments of the rear arm of the switch 21, and which adjustment is, as shown, accomplished by adjustments of the screw 27. 20 Assume that the adjustment of the screw 27 is such that under the relative rapid expansion of the sole plate and the relatively slower expansion of the bar 29, the latter, acting on the switch 21, will separate the contact points 25 19 and 20 when the temperature of the sole plate reaches 500 degrees F. The instant that the circuit is thus broken by the separation of the contacts 19 and 20, the temperature of the sole plate of the flatiron and all other parts 30 of the flatiron, for that matter, will commence to recede, but the temperature of the sole plate will decrease more rapidly than that of the actuator bar 29, and there will be a lag in the lowering of temperature and hence the contraction of the bar 29 in respect to the lowering of temperature and contraction of the sole plate. The bar 29 tends to maintain, for a short interval, the length that is assumed at the instant of breaking of the circuit, and while the 40 sole plate is making its initial contraction. This permits the initial contraction of the sole plate to again close the switch, thereby again turning on the current as soon as the sole plate of the flatiron has been very slightly 45 reduced, to wit: from 500 degrees F. to approximately 498 degrees F.

When the current has been again turned on, and heat applied to the iron, there will be a lag in the heat absorption and an expansion of the 50 switch actuator bar 29 in respect to the rapidity of the heat-absorption and expansion of the sole plate, so that when the temperature of the sole plate has been but slightly raised, to wit: back to the predetermined desired temperature assumed to be 500 degrees F., the circuit will be again opened and the current to the heating element cut off. In actual experiments with flatirons having a switch actuator made of a material of a higher co-efficient of expansion 60 than the sole plate, it has been found that the lag will then be in the sole plate and that this lag works against accuracy of control, so that there will be a drop or variation in temperature of the sole plate of approximately 150 degrees F., 65 depending somewhat on the character of the work being ironed, but always of such material variation as to destroy accuracy of control.

The efficiency of the scheme above described, requires the switch actuator to be embedded or 70 incorporated in the sole plate so that it is subject to direct heat exchange with the sole plate and is subjected to the same temperatures; and the accuracy of the control is improved by having direct contact between the switch actuator 75

and the sole plate. Moreover, the efficiency of the flatiron is further improved by embedding the electrical heating element in the sole plate so that the three elements, to wit: the sole plate, the electrical heating element and the switch actuator, are incorporated substantially as a unit.

5 In the above description of the structure illustrated, the desired temperature is assumed to be 500 degrees F., but this predetermined temperature may obviously be varied by varying the position of the rear contact point 18 in respect to the contact point 20 through the adjustment of the screw 27 which acts on the rear 10 arm of the spring switch member 21.

15 What I claim is:

1. In an electric iron having a heating element and a supply circuit for said heating element including a switch; a sole plate, and a metallic 20 switch actuator associated with said sole plate and having a substantially different coefficient of expansion from that of the sole plate, said actuator being a nickel-steel alloy in which the nickel is in a proportion of from forty to fifty 25 percent of the total metal in the alloy, whereby said switch is operated by the differential expansion and contraction of said sole plate and actuator.

2. The structure defined in claim 1, in which 30 said actuator is in the form of a bar, one end of which actuates said switch and the other end of which reacts against the sole plate at a point remote from said switch.

3. The structure defined in claim 1, in which said switch is at the heel end of said sole plate and said actuator is in the form of a bar that acts upon said switch at its rear end and the front end of which reacts against the front 5 toe end of said sole plate.

4. The structure defined in claim 1, in which said switch actuator and said heating element are incorporated in said sole plate.

5. In an electric iron having a heating ele- 10 ment and a supply circuit for said heating element including a switch; a sole plate, and a metallic switch actuator associated with said sole plate and having a substantially different coefficient of expansion from that of the sole 15 plate, said actuator being a nickel-steel alloy in which the nickel is in a proportion of approximately 42% of the alloy, whereby said switch is operated by the differential expansion and contraction of said sole plate and actuator. 20

6. The structure defined in claim 5, in which said actuator is in the form of a bar incorporated in said sole plate.

7. The structure defined in claim 5, in which 25 said switch actuator is in the form of a bar incorporated in said sole plate adjacent the longitudinal center thereof, and in which said actuator is connected at one end to said switch and at its other end to the sole plate.
